HOUSING FOR A WRITING INSTRUMENT

Helmut Bross, Weichselgartenstrasse 40,
Altenberg, Germany

Filed Sept. 7, 1965, Ser. No. 86,867

Claims priority, application Germany June 1, 1965

Term of patent 14 years

(Cl. D74—17)

FIG. 2

FIG. 1

FIG. 3

FIG. 7

FIG. 4

FIG. 5   FIG. 6

FIG. 1 is a side view of a housing for a writing instrument showing my new design.

FIGURE 2 is a front view thereof.

FIGURE 3 is a rear view thereof.

FIGURE 4 is a top view of FIGURE 1.

FIGURE 5 is a sectional view taken on line 5—5 of FIGURE 3 and is rotated 90° with respect thereto.

FIGURE 6 is a sectional view taken on line 6—6 of FIGURE 3.

FIGURE 7 is a sectional view taken on line 7—7 of FIGURE 1.

The essential features of my design reside in the portions shown in solid lines on the drawing.

I claim:

The ornamental design for a housing for a writing instrument, as shown and described.
